WITNESS: J. J. Wright

ATTORNEY

UNITED STATES PATENT OFFICE.

JOHN W. STALDER, OF LINCOLN, NEBRASKA, ASSIGNOR OF ONE-FOURTH TO CARL STECKELBERG, OF LINCOLN, NEBRASKA.

CUE TIP.

Application filed March 18, 1925. Serial No. 16,491.

To all whom it may concern:

Be it known that I, JOHN W. STALDER, a citizen of the United States, residing at Lincoln, in the county of Lancaster and

5 State of Nebraska, have invented new and useful Improvements in Cue Tips, of which the following is a specification.

This invention relates to improvements in billiard cues, an object of the invention being to provide means for securing a tip to a cue in a manner to permit of its ready removal and the convenient substitution of a new tip.

10 Another object of the invention is the provision of means of the above character which include an attaching ferrule whose inner end engages the cue in a manner to permit of its being tightly held in place without disturbing the flush appearance of the cue and thus 15 confusing the player.

With the above and other objects in view, the invention further includes the following novel features and details of construction, to be hereinafter more fully described, illustrated in the accompanying drawings and 20 pointed out in the appended claim.

In the drawings:—

Figure 1 is a perspective view showing one 25 end of a cue having a tip attached thereto in accordance with the invention.

Figure 2 is a sectional view of the same.

Figure 3 is an elevation showing the parts in separated relation.

Figure 4 is a section on the line 4—4 of 30 Figure 2.

Figure 5 is an inner end view of the tip.

Figure 6 is an end view looking at the outer end of the tip holder or thimble.

Referring to the drawings in detail where- 35 in like characters of reference denote corre- 40 sponding parts, the reference character 10 indicates a portion of a billiard cue having a reduced end 11 and a beveled shoulder 12 at the inner end of the reduced end.

45 Threadedly mounted upon the reduced end 11 of the cue is a ferrule 13 whose inner

end is beveled as indicated at 14 so as to engage the beveled shoulder 12. The ferrule may thus be tightly screwed into position without causing an uneven ridge to form 50 upon the cue at the inner end of the ferrule, the beveled end 14 of the ferrule engaging over and substantially enclosing the beveled shoulder 12. The cue stick and ferrule are thus maintained in a substantially flush condition and the smooth surface is presented which will not distract or interfere with the player.

55 Threadedly and removably secured in the outer end of the ferrule is a thimble 15, the latter being provided with a reduced threaded extension 16 so as to form a coupling section which engages the ferrule. The opposite end of the thimble is interiorly threaded so as to threadedly and removably receive the neck 17 of a tip 18, the latter being preferably formed of fiber. The ferrule is provided with an opening 19 for the reception of a suitable instrument whereby it may be tightly adjusted in position or readily removed.

60 The invention is susceptible of various changes in its form, proportions and minor details of construction and the right is herein reserved to make such changes as properly 65 fall within the scope of the appended claim.

70 Having described the invention what is claimed is:—

In a cue, a stick having a reduced end, a ferrule threadedly secured upon said end 80 and having a tool receiving opening therein, a beveled shoulder at the inner end of the reduced end, a beveled inner end for the ferrule to engage over said shoulder, a thimble, a tip threadedly engaging one end of 85 the thimble and a reduced coupling section at the opposite end of the thimble for removable engagement with the outer end of the ferrule.

90 In testimony whereof I affix my signature.

JOHN W. STALDER.
